US0D1085878S

(12) **United States Design Patent** (10) **Patent No.:** **US D1,085,878 S**
(45) **Date of Patent:** **** Jul. 29, 2025**

(54) **BOTTLE**

(71) Applicant: **NIAGARA BOTTLING, LLC**,
Diamond Bar, CA (US)

(72) Inventors: **Peter N. Bruinooge**, Chino, CA (US);
Katie Aihuong Nguyen, Irvine, CA
(US); **Naser Imran Hossain**, Aliso
Viejo, CA (US); **Gregory N. Boucher**,
Brea, CA (US); **Abhishek Shukla**,
Chino Hills, CA (US)

(73) Assignee: **Niagara Bottling, LLC**, Diamond Bar,
CA (US)

(**) Term: **15 Years**

(21) Appl. No.: **29/775,875**

(22) Filed: **Mar. 25, 2021**

(51) LOC (15) Cl. **09-03**

(52) U.S. Cl.

USPC **D9/500**; D9/502

(57) **CLAIM**

The ornamental design for a bottle, as shown and described.

DESCRIPTION

FIG. 1 is a top perspective view of a bottle.

FIG. 2 is a bottom perspective view of the bottle shown in FIG. 1.

FIG. 3 is a left side view of the bottle shown in FIG. 1; and, FIG. 4 is a right side view of the bottle shown in FIG. 1. The dash-dot broken lines represent portions of the article that form no part of the claimed design. The dash-dot broken lines represent boundaries of the claimed design and form no part of the claimed design. Any surfaces inside the bottle form no part of the claimed design.

1 Claim, 3 Drawing Sheets
